DETACHABLE WIRE FRAME FOR
BRASSIÈRESLee Fairbanks, Jackson Heights, N. Y., and
Paul Rosenfeld, Newark, N. J.

Application July 14, 1949, Serial No. 104,752

1 Claim. (Cl. 2—302)

2

1 This invention relates to a detachable wire frame for brassières.

The principal object of this invention is the provision of a wire frame for brassières which may readily be attached thereto by the ultimate user and which may equally as readily be detached therefrom for cleaning and other purposes.

Wire framed brassières are well known to the brassière industry. Such brassières are generally quite expensive and if a proper fit is desired, the brassière and its wire frame must be individually fitted to the person of the wearer. The attachment of wire frames to brassières is, today, a professional matter which only experienced brassière makers are able to accomplish. There are no wire frames available at the present time which the average woman would be able to attach to a brassière with the sewing skill and means which are available to her.

The present invention provides a wire frame for brassières which can very easily be attached to the brassières by women who are inexperienced in the brassière making art. It comprises a wire frame which is mounted in a cloth sheath, a cloth tape of substantially the same shape as said wire frame and its said cloth sheath, and means for detachably securing the cloth sheath to said cloth tape. The tape may be sewed by any person capable of using a sewing needle or operating a sewing machine, to an ordinary brassière. The sheath with its wire frame mounted therein may then very easily and quickly be attached to said tape, and the brassière thereby acquires the characteristics of a wire frame brassière. In the preferred form of this invention snap fasteners are utilized as the means for detachably securing the wire sheath to the tape. It will be appreciated, therefore, that said sheath with its wire mounted therein may very readily be detached from the brassière for laundering and other purposes, as and when desired.

Not only is the sheath and its wire frame mounted therein readily detachable from the brassière, but said wire frame is equally as readily removable from its said sheath. In the preferred form of this invention, the wire frame includes two arms or wings and the sheath is accordingly made in two parts, one for each of said arms or wings. The wire frame may be mounted in its said sheath by simply inserting its two arms into the two parts of the sheath. This is a highly desirable feature since it renders it possible to launder the sheath without damaging the wire frame.

It will be seen from the foregoing that the present invention is capable of converting or transferring a conventional wireless brassière to a wire framed brassière. Since the wire frame is just as easily detachable from the brassière as it is attachable thereto, a wire framed brassière made in accordance with the present invention may be reconverted to a wireless type of brassière by the simple expedient of removing its wire frame.

What has been said above with respect to brassières is equally true of foundation garments having brassière attachments. It is also equally true of halter-type garments and of bathing and swimming suits. In each case a wireless garment may be converted to a wire framed garment by simply attaching the wire frame attachment herein described and claimed.

It is important to note that the wire frame attachment herein claimed may be attached to the wireless garment by the individual owner and user thereof so that in each case the wire frame attachment may be individually fitted to the individual requirements of the wearer. In other words, a wire framed brassière or similar garment may be had in each case which will be similar in fit and comfort, as well as in function, to the custom-made brassières of professional brassière makers.

Another important object of this invention is the provision of a wire frame attachment for brassières which is adapted to convert a shoulder strap type of brassière to a strapless brassière. The wire frame attachment constituting the present invention may be secured to the brassière in two ways: it may be placed under the bust pockets and it may be placed above the bust pockets. In the first case the attachment transforms an ordinary wireless strap type of brassière to a wire frame strap type of brassière; in the second case the attachment transforms an ordinary strap type of brassière to a wire framed strapless brassière. In both cases, however, the wire frame attachment is detachable without difficulty so that the brassière may be laundered without damaging the wire.

The wire frame attachment herein described and claimed may take many forms and all of these forms are herein contemplated and included within the scope and coverage of the claim. One preferred form is shown solely for purposes of illustration in the drawing wherein:

Fig. 1 is a perspective view of a brassière incorporating the wire frame attachment of the present invention, the inside of said brassière being shown;

Fig. 2 is a front view of the wire frame and sheath parts of the wire frame attachment shown in Fig. 1;

Fig. 3 is an end view thereof looking in the direction of arrows 3-3 in Fig. 2;

Fig. 4 is a back view of the tape member of said wire frame attachment, to which the sheath may be attached; and

Fig. 5 is a front view of the wire frame itself.

Brassière 10 shown in the drawing is illustrative of the different garments to which the present invention is applicable. What is herein said, therefore, regarding brassières, is equally true of halter-type garments and swim suits and the like. The brassière shown in the drawing comprises a body portion 11 and a pair of bust pockets 12 and 13 respectively. A pair of back straps 14 and 15 respectively and hooks and eyes 16 and 17 respectively secure the brassière to the person of the wearer.

Sewed to the brassière, adjacent and outlining the bust pockets, is a tape 20. This tape may be made of cloth or any conventional textile fabric or any other suitable material. It is looped over upon itself at its center portion and it is curved between its said looped center portion and its end portions to form a pair of wings which correspond to the curvature of the bust pockets. A plurality of female snap fastening members 21 is fastened to said tape along virtually its entire length.

Supported by said tape is a sheath 25 and it will be seen from the drawing that said sheath may comprise two separate and separable parts, each constituting a sheath or sheath member. This sheath assumes the same shape as tape 20 and it is provided with a plurality of male snap fastening members 26 spaced in accordance with the spacing of the female snap fastening members 21. It will be understood that these male and female snap fastening members are adapted to coact with each other so that the sheath may be detachably secured to the tape by means of said snap fastening members. The sheath may be made of tubular material such as cloth tubing or tubing made of any suitable textile fabric. In the preferred form of this invention the sheath comprises a tube which is made by sewing two strips of material to each other along their respective edges; a strip of tape material 27 and a strip of plush material 28. The plush material faces on the inside of the garment to provide a cushioning effect against the person of the wearer. The snap fastening elements 26 are attached, however, to the tape material 27, since that is a stronger material and it faces the tape 20.

A wire frame 30 is provided for the attachment herein claimed and it will be seen that it comprises a single length of wire which is looped at its center portion 31 and is provided with end loops 32 and 33 respectively and which is curved or bowed between its center loop 31 and its end loop 32 and between its said center loop and its other end loop 33. The curvature of the wire frame between its said center loop and its two end loops corresponds to the curvature of the bust pockets. This wire frame should be made of spring material such as resilient stainless steel. Its two bowed wing portions may be inserted into the corresponding parts of the sheath as Fig. 2 clearly shows. It will be seen, however, that the center loop portion 31 projects upwardly and outwardly from the sheath and a cover for said loop portion is therefore pro-

vided on tape 20 as Figs. 1 and 4 clearly show. This cover comprises a strip of material 35 which is sewed to the central fold of tape 20. This strip of material 35 may then be folded over upon itself as shown in Fig. 1 to form a pocket for the wire loop 31. It may then be sewed to the brassière so that it will function permanently as a pocket for the wire loop. Since part of the pocket faces the person of the wearer, the material of which said pocket is made may be the same plush material of which sheath sections 28 are made.

It has above been stated that this wire frame attachment may be incorporated into a shoulder strap type of brassière to convert it to a strapless brassière. This may be done by taking the very same attachment which has above been described and inverting it and in that way attaching it to the brassière, above the bust pockets instead of below them. It is the same attachment that is used and the same method and means of attaching it to the brassière; the sole difference is that in the one case it is attached below the bust pockets and in the second case it is attached above them.

It will be appreciated that the foregoing is descriptive of preferred forms only of the several parts of the attachment herein claimed and that these forms may be modified in many ways without departing from the basic principles of the invention. For example the wire frame is shaped in one preferred way. It may be shaped in many other ways and yet be usable and useful in connection with the present invention. In its preferred form it is made of spring metal but other material, such as strong, springy plastics may be used to equal advantage.

Another illustration of the way this preferred form of the invention may be modified without altering the invention itself is to be found in the method and means of affixing the tape to the brassière. It has above been stated that the tape may be sewed to the brassière. This is a practical way of attaching the tape to the brassière, but it will be obvious that there are other methods as, for example, by the use of a cement or other suitable adhesive.

We claim:

A wire frame attachment for brassières and the like, comprising a cloth tape which consists of two arcuate portions joined together at one end, a pair of arcuate cloth sheaths, snap fasteners on said tape and said sheaths for detachably securing said sheaths to said tape, and a wire frame having two arcuate portions which are joined together at one end, said arcuate portions of the wire frame being removably inserted in said cloth sheaths.

LEE FAIRBANKS.
